UNITED STATES PATENT OFFICE.

CHARLES W. YERGER, OF MILWAUKEE, WISCONSIN, ASSIGNOR TO THE CUTLER-HAMMER MFG. CO., OF MILWAUKEE, WISCONSIN, A CORPORATION OF WISCONSIN.

MOTOR-CONTROLLER.

1,157,277.

Specification of Letters Patent. Patented Oct. 19, 1915.

Application filed June 22, 1911. Serial No. 634,712.

To all whom it may concern:

Be it known that I, CHARLES W. YERGER, a citizen of the United States, residing at Milwaukee, in the county of Milwaukee and 5 State of Wisconsin, have invented new and useful Improvements in Motor-Controllers, of which the following is a full, clear, concise, and exact description, reference being had to the accompanying drawing, forming 10 a part of this specification.

My invention relates to controllers for electric motors.

One object of my invention is to provide 15 a controller which will enable the use of a motor for different duties with convenience and safety.

A further object of my invention is to provide a controller which will insure 20 equally good conditions of acceleration of the motor in its performance of different duties.

Further advantages and objects of my invention will be hereinafter set forth.

My invention is particularly applicable 25 to the control of motor-operated elevators where it is desired to use the same for both passenger and freight duty but is not limited to this particular use or application.

Heretofore, where it has been desired to 30 use the same motor for both passenger and freight elevator duty it has been found necessary to provide what is commonly termed "back-gearing" to compensate for the load variations in the different classes 35 of service. In freight service the load conditions are much more severe than in passenger service but the speed requirements in the former are much more lax than in the latter. As is well understood by those 40 skilled in the art, by reducing the speed of lift of a given load the power required for lifting is decreased. Hence back-gearing was employed to compensate for varying loads by varying the speed ratio between 45 the load and the motor to protect the motor against overload. This method however, is open to many objections among which may be mentioned the necessity for a more or less complicated and costly gear mechanism, 50 and the loss of much time and labor in changing the gearing for the different classes of service.

By the employment of my invention a motor may be easily and expeditiously, and 55 in a better and more efficient manner adapt-

ed for different classes of service by mere regulation of electrical means, and in a preferred form of my invention, by the manipulation of but a single switch.

As above stated it should be understood 60 that my invention is not limited to the above application but may be used in various other relations and for various other purposes.

For the purpose of more clearly and fully 65 setting forth the nature and characteristic features of my invention I shall describe the controller diagrammatically illustrated in the accompanying drawing. It should be understood, however, that the embodiment of my invention shown in the accompanying drawing has merely been selected for the purpose of illustration and that my invention is susceptible to embodiment in 70 various other forms.

The controller diagrammatically illustrated in the accompanying drawing is particularly applicable to elevator control. Accordingly, for the purpose of this explanation, let it be assumed that the motor 1, 75 shown in the drawing, is employed for operating an elevator. Compound wound motors are preferable in elevator service and I have accordingly shown the motor 1 as provided with an armature A, a series field winding F and a shunt field winding f.

In series with the motor armature are the usual starting resistances r , r' , r^2 , and r^3 , it of course being understood that any number of these resistances may be employed. 80 For controlling the resistances r , r^1 , r^2 , and r^3 , I have provided switches 2, 3, 4 and 5 respectively and for controlling the continuity of the motor circuit I have provided a main switch 6. The switches 2, 3, 85 4, 5 and 6 are provided with operating windings 2^a , 3^a , 4^a , 5^a , and 6^a respectively. In practice these windings may be controlled in any preferred manner, but for the purpose of illustration I have shown all of 90 100 said windings connected to a common conductor, controlled by a single pole, switch 7. I have also provided each of the switches with an auxiliary contact, designated by the corresponding reference numeral with the 105 exponent b , for closing the circuit of the operating winding of the next succeeding switch, whereby said switches are successively energized automatically upon closure of the switch 7. Associated with each of 110

- the switches 6, 2, 3, and 4 is a current relay switch, given the same reference numeral as its corresponding switch, with the exponent c . Each of these relay switches is 5 adapted to control the circuit of the operating winding of the next succeeding switch and is provided with an operating winding adapted upon closure of its corresponding switch to be included in the motor circuit. 10 These relay switches serve in a well known manner to temporarily check the progressive operation of the resistance controlling switches upon excessive surges of current in the motor circuit to protect the motor 15 against injury. Of course in practice other protective means and interlocks to protect the motor may be employed, but it has been deemed unnecessary to disclose any further protective means herein. The foregoing 20 provides means for starting the motor and bringing the same up to normal speed, and as will be hereinafter more clearly and fully set forth short circuits the series field winding of the motor when the motor is substantially brought to normal speed.

In addition to the above described starting or accelerating means I have provided means for weakening the shunt field winding after the motor has been brought up to a normal 25 speed to further increase the speed thereof. This means includes a resistance 8, in series with the shunt field winding and normally short circuited by a switch 9. The switch 9 is provided with an operating winding 10, 30 controlled by an auxiliary contact 5^b of the switch 5, in such a manner as to be energized only upon closure of said switch 5. To further insure against premature response of the switch 9 I have provided, in conjunction 35 with the switch 5, a relay switch 5^c. This relay switch is in series with the operating winding of switch 9 and has an operating winding adapted upon closure of the switch 5 to be connected in the motor circuit to insure 40 against energization of the switch 9 while abnormal current conditions prevail in the motor circuit.

For passenger elevator service only so much of the controller as has been above described would be utilized and therefore before proceeding further I shall describe the mode of operation and functions of so much of the controller. Assume that current is supplied to the motor and to the windings of 55 the various switches from supply lines 15 and 16. With the several switches in the positions illustrated, the motor would be disconnected from circuit.

To start the motor it is only necessary to 60 close the switch 7. Thereupon circuit is closed from main line 15 by conductor 17 through the operating winding of main switch 6 to conductor 18 and thence to main line 16. The establishment of this circuit 65 causes the switch 6 to respond and close the

motor circuit as follows:—From main line 15 through switch 6 by conductor 19 through the winding of relay switch 6^c by conductor 20 through all of the resistances r , r' , r^2 and r^3 by conductor 21 through the 70 series field winding F of the motor by conductors 22 and 23 through the motor armature by conductors 24 and 25 to main line 16. Also circuit is closed from switch 6 by conductors 27, 28 and 29 through the shunt field 75 winding f of the motor by conductor 30 through switch 9 and conductor 31 to conductor 25. The motor is thus started but with all of the starting resistances in circuit. However, upon closure of switch 6 the auxiliary contact 6^b thereof completes a circuit from switch 6 through relay 6^c and thence through the operating winding of the first accelerating switch 2 to conductor 18. If the relay switch 6^c is not caused to respond upon 80 closure of the motor circuit, the operating winding of switch 2 would be immediately energized and close said switch. If however, the relay switch 6^c does respond upon closure of the motor circuit, the circuit 85 through the operating winding of switch 2 will of course not be completed until the relay drops its plunger upon the restoration of normal conditions in the motor circuit. The relay 6^c and likewise the remaining relays 90 may be adjusted to respond at any desired current values. Upon closure of switch 2 the resistance r is short circuited, said short circuit extending from switch 6 by conductors 27, 28 and 35 through the switch 2 by conductor 36 through the operating winding of 95 relay 2^c by conductor 37 to a point between the resistances r and r' . Also upon closing switch 2 through its auxiliary contact 2^b completes the circuit of the operating winding 100 of the next accelerating switch 3 through the relay switch 2^c. Accordingly said switch 3 cannot respond until the return of the relay switch 2^c to closed position in the event 105 that it responds upon closure of switch 2. Closure of switch 3 completes a short circuit around resistance r' from conductor 28 through said switch 3 by conductor 38 110 through the winding of relay 3^c by conductor 39 to a point between resistances r' and r^2 . Closure of switch 3 also completes 115 through its auxiliary contact 3^b the circuit of the operating winding of switch 4 through the relay switch 3^c and said switch 4 when closing short circuits the resistance r^2 . This short circuit extends from conductor 28 by conductor 40 through the switch 4 thence through the operating winding 120 of relay 4^c by conductor 41 to a point between resistances r^2 and r^3 . Also upon closing switch 4 completes the circuit of the operating winding of switch 5 through its auxiliary contact 4^b and the relay switch 4^c. Switch 5 in closing short circuits both the 125 resistance r^3 and also the series field winding 130

F of the motor. This short circuit extends from conductor 28 by conductor 42 through switch 5 by conductor 43 through the winding of relay 5^e to conductor 23 and thence to 5 the motor armature as already traced. The purpose and advantage of short circuiting the series field winding being well understood in the art, it is needless to herein explain the same. Of course the series field 10 need not be short circuited unless desired.

It will thus be seen that closure of control switch 7 first causes completion of the motor circuit and then gradual removal of the resistances r , r' , r^2 and r^3 to bring the motor 15 up to normal speed with the series field winding short circuited. Likewise it will be seen that this acceleration is governed by the relay switches to protect the motor against excessive surges of current.

20 Switch 5 upon closing completes through its auxiliary contact 5^b a circuit through the relay 5^e by conductor 44, through the operating winding 10 of switch 9 by conductor 45, through a switch hereinafter described to conductor 25. This causes energization of the switch 9 which upon responding opens the short circuit around resistance 8 thereby throwing said resistance in series with the shunt field winding f . 25 This of course weakens the shunt field winding of the motor and further increases the speed thereof. The relay 5^e in circuit with the operating winding of switch 9 prevents response of said switch until the desired 30 current conditions are established in the motor circuit.

To stop the motor it is only necessary to open the switch 7 whereupon all of the switches previously mentioned will drop 40 out, thereby disconnecting the motor from circuit. Of course in practice reversing means may be used, but it has been deemed unnecessary to show or describe the same herein.

45 The controller above described will obviously give the high speed desired for passenger elevator service and duly protect the motor in such service where the load is confined within predetermined limits.

50 I shall now describe the means for adapting the above controller and accordingly the motor to freight or other heavier and more severe duty. This means includes a switch 46 in series with the operating winding of switch 10 and adapted upon use of the motor for the heavier and more severe service mentioned to be opened to prevent response of the switch 9. This insures the maintenance of the short circuit around the 55 resistance 8 and consequently full shunt field strength, and a reduction in the maximum speed of the motor. Under these conditions the motor can obviously be safely used to lift a greater load than under the 60 previously described maximum speed condi-

tions since the power thus required at the speed obtainable would be no greater. However, in this heavier and more severe duty more power is required for starting the motor and bringing the same up to speed 70 than in the previously considered service. To meet these conditions I have provided an auxiliary set of resistances r^4 , r^5 , r^6 , and r^7 which I connect in parallel to the resistances r , r' , r^2 and r^3 respectively. Provision of these parallel resistances obviously 75 permit a greater flow of current to the motor during the starting period. Equally obviously the degree of increase of current is dependent upon the value of the auxiliary resistances, and accordingly may be regulated as desired. For connecting these auxiliary resistances in circuit any suitable form of switch either manual or automatic may be employed. I have shown a double pole knife switch 47 and have provided an interlock between said knife switch and switch 46, whereby when switch 47 is closed the switch 46 is opened and conversely when the switch 47 is opened, the switch 46 is closed. This interlock comprises a lug 48 on the knife switch adapted when the same is opened to engage and close switch 46 which is normally biased to open position 80 by a spring 49. Of course in practice any other desired form of interlock may be employed. Thus I positively insure against field weakening when the switch 47 is thrown in to adapt the controller to the 85 heavy and more severe service mentioned.

When desired to use the motor for freight elevator or like service, it is merely necessary to close the switch 47 and operate the controller as above described. The additional circuits established under these conditions are as follows:—Upon closure of main line switch 6 the current divides at the stationary contact of said switch, one branch extending as above described, while the other branch extends by conductor 50 through the resistance r^4 by conductor 51 to the left hand blade of switch 7, thence through said blade and by conductor 52 through resistances r^5 and r^6 by conductor 53 through the right hand blade of switch 47 by conductor 54, through the resistance r^7 to conductor 21 where it reunites with the other branch. Thus the resistances r^4 , r^5 , r^6 and r^7 are connected in parallel to the resistances r , r' , r^2 and r^3 as above set forth and with the results aforesaid. Upon closure of switch 2 to short circuit resistance r a short circuit is also established by said switch around the resistance r^4 . This short circuit is established from the left hand terminal of resistance r^4 by conductors 50, 28 and 35 through switch 2 by conductor 36 and conductor 55 to the intermediate contact of the left hand blade of switch 47, thence to conductor 51 and the right hand 90

terminal of resistance r^4 . Closure of switch 3 establishes in addition to the short circuit around the resistance r' a short circuit around the resistance r^5 . This short circuit 5 extends from conductor 28 through switch 3 by conductors 38 and 56 to a point between the resistances r^6 and r^7 . Closure of switch 4 in addition to short circuiting resistance r^2 also short circuits resistance r^8 .
10 This latter short circuit extends from conductor 28 by conductor 40 through the switch 4 by conductors 57 to the intermediate contact of the right hand blade of switch 47, thence through said blade to conductor 15 53 leading from resistance r^6 . Switch 5 in addition to short circuiting resistance r^3 and the series field winding of the motor also short circuits resistance r^7 . This latter short circuit extends from conductor 28 through 20 the switch 5 by conductor 43 through the coil of relay 5 which of course now serves no purpose, to conductor 23, and thence to the motor armature.

It will thus be seen that I am enabled to 25 control the auxiliary resistances without the necessity of providing any additional control switches. It will further be observed upon tracing the circuits of these auxiliary resistances that each is connected in parallel 30 and not in series with the current relay governing its corresponding control switch. Accordingly only the current traversing the parallel path will pass through the relay windings and thus the flow of current 35 through said windings will remain substantially unchanged. Therefore the relays will respond under substantially the same current conditions as before thereby insuring equally good and safe conditions of acceleration 40 under the heavier load condition.

What I claim as new and desire to secure by Letters Patent is as follows:—

1. The combination with an electric motor, of accelerating means therefor and 45 electrical means for compensating for load variations in starting to thereby adapt said accelerating means to changes in the load on the motor.

2. The combination with an electric 50 motor, of power controlling means therefor to accelerate the same by successive increments of power and means to adjust said former means to different load conditions by varying the individual values of said 55 power increments.

3. In a controller for electric motors in combination, a plurality of resistances, a plurality of separately actuated switches controlling said resistances to gradually accelerate the motor, a plurality of auxiliary resistances and means for connecting each of said auxiliary resistances in parallel with one of said first mentioned resistances to vary the amount of current supplied to the 65 motor during the acceleration thereof.

4. In a controller for electric motors in combination, a plurality of resistances, a plurality of the separately actuated switches for controlling said resistances to gradually accelerate the motor, a plurality of auxiliary 70 resistances and a single switch for connecting each of said auxiliary resistances in parallel to one of said first mentioned resistances to vary the amount of current supplied to the motor during the acceleration 75 thereof.

5. The combination with an electric motor, of current controlling means therefor to accelerate the same by a given number of current increments, and means for varying 80 the individual values of said current increments to compensate for the effect of load variations on said motor in starting.

6. In a controller for electric motors in combination, a plurality of resistance sections, a plurality of separately actuated switches each adapted to short-circuit one of said resistance sections to accelerate the motor, a plurality of auxiliary resistance sections and a single switch for connecting 90 said auxiliary resistance sections to said first mentioned resistance sections, each of the former in parallel with one of the latter.

7. In a controller for electric motors, in combination, automatic accelerating means 95 for the motor, electroresponsive means for arresting the operation of said first mentioned means upon the occurrence of abnormal conditions in the motor circuit, and means independent of said accelerating 100 means for varying the amount of current supplied to the motor by said accelerating means without affecting the adjustment of said electroresponsive means.

8. In a controller for electric motors in 105 combination, means for accelerating the motor in steps, means responsive to current conditions in the motor circuit for controlling said accelerating means, and means for varying the amount of current supplied 110 through said accelerating means without varying the flow of current through said current responsive means.

9. In a controller for electric motors, the combination with resistance varying means 115 for gradually accelerating the motor, means responsive to current conditions in the motor circuit for governing the operation of said resistance varying means, and means for varying the resistance controlled by said resistance varying means without varying the current flow through said current responsive means.

10. In a motor controller in combination, a resistance in the motor circuit, a switch 125 for controlling said resistance, a relay device for governing the operation of said switch, said relay having an operating winding connected in the motor circuit in series with said resistance and a second resistance 130

adapted to be connected in parallel to said first mentioned resistance and the operating winding of said relay device to increase the flow of current in the motor circuit without 5 increasing the flow of current through the operating winding of said relay device.

11. In a motor controller in combination, a resistance in the motor circuit, a switch for controlling said resistance, a relay device for governing the operation of said switch, said relay having an operating winding connected in the motor circuit in series with said resistance, and a second resistance adapted to be connected in parallel to said 10 first mentioned resistance and the operating winding of said relay device to increase the flow of current in the motor circuit without increasing the flow of current through the operating winding of said relay device said 15 second resistance being controllable by said switch.

12. In a controller for electric motors in combination, a plurality of resistances in the motor circuit, a plurality of switches for gradually removing said resistance, a plurality of relay devices for governing the operation of said switches, each of said relay devices having an operating winding connected in series with the motor, a second 20 resistance, and means for connecting said second resistance in parallel with said first mentioned resistance to be gradually removed simultaneously therewith by said switches, the flow of current through the 25 windings of said relay devices being unaltered by the connections of said second resistance.

13. In a controller for electric motors in combination, means for gradually starting 40 the motor and after bringing the motor up to normal speed to further accelerate the same, and means for increasing the power available for starting the motor and restricting the speed obtainable with said first 45 mentioned means.

14. In a controller for electric motors in combination, means for starting the motor

and regulating the speed thereof, means for regulating the power available for starting the motor by said first mentioned means, 50 and means for restricting the speed obtainable with said first mentioned means, said last two mentioned means being interlocked to insure operation of one upon operation of the other. 55

15. In combination, an electric motor, means for accelerating said motor to normal speed and thereafter weakening the field thereof for further acceleration, means for varying the amount of current supplied 60 to the motor by said first-mentioned means, and an interlock between said means for rendering said first-mentioned means ineffective to weaken the field of said motor under predetermined conditions. 65

16. The combination with an electric motor, of automatic accelerating means therefor controlled in its operation by the electrical conditions in said motor, and means associated with said accelerating 70 means to electrically compensate for the effect of load variations on said motor in starting without effecting the aforesaid control of said accelerating means.

17. The method of accelerating an electric 75 motor by a predetermined number of increments of power and pre-arranging compensation for different load conditions by adjustment of the individual values of such power increments. 80

18. The method of accelerating an electric motor under different load conditions consisting in increasing the power supplied to the motor in a given number of steps irrespective of load conditions and varying the 8 individual ranges of such steps according to the load conditions.

In witness whereof, I have hereunto subscribed my name in the presence of two witnesses.

CHARLES W. YERGER.
